UNITED STATES PATENT OFFICE.

EDNA FLORENCE STEFFENS, OF CLEVELAND HEIGHTS, OHIO.

DESIGN FOR A STATUETTE.

48,657.

Specification for Design.

Patented Feb. 29, 1916.

Application filed November 2, 1915. Serial No. 59,327. Term of patent $3\frac{1}{2}$ years.

To all whom it may concern:

Be it known that I, EDNA F. STEFFENS, a citizen of the United States, residing at Cleveland Heights, in the county of Cuyahoga and State of Ohio, have invented a new, original, and ornamental Design for Statuettes, of which the following is a specification, reference being had to the accompanying drawing, forming part hereof, wherein—

I claim:—

The ornamental design for statuettes as shown.

EDNA FLORENCE STEFFENS.

Witnesses:

HENRIETTA M. STEFFENS,
GEORGE RUGGE.
